CLAIM

The ornamental design for an LED wall mounted lamp, as shown and described.

DESCRIPTION

FIG. 1 is a perspective view of a LED wall mounted lamp showing the claimed design;

FIG. 2 is another perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 depicts the LED wall mounted lamp in an alternate position of use; and,

FIG. 10 depicts the LED wall mounted lamp in another alternate position of use.

The broken lines depict portions of the LED wall mounted lamp that form no part of the claimed design.
